(57) CLAIM

I Claim the ornamental design for a bottle, as shown and described.

DESCRIPTION

FIG. 1 is a front elevation view of a bottle showing my new design;

FIG. 2 is a left side elevation view thereof, the right side elevation view being a mirror image;

FIG. 3 is a top plan view thereof;

FIG. 4 is a bottom plan view thereof;

FIG. 5 is a front elevation view of the closure portion of the bottle of FIG. 1, shown at an enlarged scale;

FIG. 6 is a side elevation view thereof, the opposing side being identical;

FIG. 7 is a top perspective view thereof;

FIG. 8 is a bottom plan view of the bottom element of the body of the bottle of FIG. 1 shown at an enlarged scale; and, FIG. 9 is a bottom perspective view thereof.

The broken lines in the drawings illustrate the portions of the design that form no part of the claim.
